UNITED STATES PATENT OFFICE.

JOSEPH EDW. CONAWAY, OF BALTIMORE, MARYLAND.

SAFETY DEVICE FOR SUBMARINE BOATS.

1,127,965.

Specification of Letters Patent.

Patented Feb. 9, 1915.

Application filed June 17, 1913. Serial No. 774,200.

To all whom it may concern:

Be it known that I, JOSEPH E. CONAWAY, a citizen of the United States, residing at Baltimore, in the State of Maryland, have 5 invented certain new and useful Improvements in Safety Devices for Submarine Boats; and I do hereby declare the following to be a full, clear, and exact description of the invention, such as will enable others 10 skilled in the art to which it appertains to make and use the same.

This invention relates to submarine boats and has for an object to provide a tank which forms an intermediate section in the 15 boat and is capable of being detached from the boat as a means for bringing the crew to the surface.

A still further object is to provide a separate compartment in the boat for the 20 reception of the tank, which compartment may be flooded to raise the tank from the boat.

A still further object is to provide novel 25 means for normally securing the tank stationary in the compartment.

A still further object is to provide means 30 for automatically establishing communication between the tank and the atmosphere when the tank comes to the surface.

With the above object in view the invention 35 consists of certain novel details of construction and combination of parts herein-after fully described and claimed, it being understood that various modifications may be made in the minor details of construction 40 within the scope of the appended claim.

In the accompanying drawings illustrating 45 this invention: Figure 1 is a side elevation of a conventional submarine boat showing the compartment and tank in section. Fig. 2 is a fragmentary plan view. Fig. 3 is a fragmentary plan view with the tank removed. Fig. 4 is a cross sectional view on the line 4—4 Fig. 1 with the tank in normal position. Fig. 5 is a similar cross sectional 50 view to Fig. 4 with the tank removed. Fig. 6 is a longitudinal sectional view through the air valve. Fig. 7 is a longitudinal sectional view through the tank attaching means. Fig. 8 is a fragmentary view in elevation showing the tank door.

Referring now to the drawings in which like characters of reference designate similar parts, 10 designates a conventional submarine boat. Preferably located midway 55 between the ends of the boat so as to be within convenient reach of the crew there is dis-

posed a cylindrical casing 11 which forms a separate compartment in the boat and opens through the deck of the boat in a flanged mouth 12. There are pipes 13 disposed to 60 connect the casing with the sides of the boat, such pipes being controlled by valves 14 disposed exteriorly of the casing and operable when it is desired to drain the casing without pumping the water therefrom after 65 the boat rises to the surface when a test is being made of the life saving apparatus hereinafter described during a drill or the like.

A cylindrical tank 15 is disposed within 70 the casing and is spaced on all sides from the sides and bottom of the casing whereby there exists an air space 16 between the tank and the casing. The tank is closed by a convex cover 17 which is riveted or otherwise secured in place as shown at 18 and bears upon the flanged mouth 12 of the casing. The cover is provided with a man-hole 19 through which the occupants of the tank may leave the tank when it reaches the 75 surface, entry to the tank when in the boat being effected by means of doors as will presently be described.

The tank is normally anchored stationary 80 within the casing by means of a screw 20 85 which passes through a stuffing box 21 in the floor of the tank and threads into a nut 22 carried stationary in a block 23 that is bolted as shown at 24 or otherwise rigidly secured to the floor of the casing. The screw 90 is provided with a head 25 having lateral lever openings 26 into which a bar or other lever may be inserted to rotate the screw and back it out of the nut whereby to detach the tank from the casing. When so 95 detached, the casing is flooded whereby the tank floats out of the boat and rises to the surface.

For flooding the casing after the crew 100 has entered the tank, I provide a plurality of flooding pipes 27 that open through the cover of the tank and through the side wall thereof, each pipe being controlled by a valve 28. After the crew has entered the tank, these valves are opened with a resultant rush of water into the space 16 and air out of the space until the casing is completely flooded and the buoyant tank now floats out of the boat as soon as the screw is retracted to free the tank from the casing.

There are anti-friction rollers 29 disposed 110 on the inner wall of the casing and engag-

ing the outer wall of the tank which rollers facilitate the tank rising out of the casing freely and easily regardless of whether the boat is resting on an even keel or not. Dis-
 5 posed at opposite points on the outside of the tank are doors 30 each of which is slid-
 ably mounted on a track 31 that is equipped with anti-friction rollers 32 which engage the top and bottom edges of the door, the
 10 door being equipped on the inner side with a handle 33 by means of which the door may be slid closed after the crew enters the tank. The door is equipped with a gasket around the edges and may be drawn inwardly to
 15 compress this gasket and form a water-tight joint by means of yokes 34 disposed on the inner face of the door and engageable with the inner wall of the tank. Hinged doors 35 are arranged in the walls of the casing and
 20 swing outwardly from the casing, there being handles 36 on the door to facilitate their being swung open. The doors are equipped with yokes 37 which engage with the inner wall of the casing when the doors are closed
 25 and draw the doors tightly closed thereby compressing the gaskets carried by the doors to prevent leakage from the casing into the boat when the casing is flooded.

The operation is as follows: When the
 30 submarine boat has met with an accident and has sunk, the crew at a predetermined signal rush from both ends of the boat and swing open the casing doors 35, and enter the tank, it being understood that the doors
 35 of the latter are normally left open to facilitate quick access to the tank in an emergency. After entering the tank, should there be time, the casing doors are closed and locked closed by means of their
 40 yokes, otherwise are left open. The doors of the tank are closed and locked closed by their yokes 34. The crew now open the flooding valves 28 with a resultant flooding of the casing. The screw 20 is now retracted
 45 to free the tank from the casing, whereupon the tank being buoyant by virtue of the air contained therein, floats out of the casing to the surface. For supplying the tank with air after it comes to the surface a branched
 50 pipe 39 is mounted in the cover of the tank

and is equipped within the tank with a controlling valve 40. Above the tank 17 is mounted a casing 42 having an inverted frusto-conical bottom with a valve seat at its apex, the valve seat being shown at 44, 55 through which the air enters when the tank is only partly submerged and passes through the branches of the air pipe 39 into the casing, it being noted that these branches pass through the bottom of the casing. A float 60 valve 45 is provided for the valve seat 44 and is carried by a rod 43, the lower end of which is slidably mounted in a guide 43' on the tank 17, while the upper end is slidably mounted in a guide in a cross bar in the 65 casing 42, as illustrated. With this construction it will be seen that when the boat is above the surface, the float valve 45 is in the lowered position illustrated in Fig. 6 so that air may enter the casing and be 70 drawn from it through the branches of the pipe 39. When, however, the boat sinks below the surface, the valve 45 rises into the valve seat 44 and entrance of water into the casing 42 is prevented. It of course will 75 be understood that the gaskets are employed wherever desired.

From the above description it will be seen that I have provided an extremely simple and effective device for saving the crew of a 80 sunken submarine boat.

What is claimed, is:—

The combination with a submarine boat of a float tank removably mounted therein, a cover on said tank, an upwardly projecting dome carried by said cover, vertical rods supporting said dome, a plurality of vertical pipes entering said dome from said tank, a downwardly projecting conical valve seat normally open to the air centrally of the interior of said dome, a buoyant valve centrally beneath said seat adapted to close said valve when said valve is immersed in water. 85 90

In testimony whereof, I affix my signature, in the presence of two witnesses.

JOSEPH EWD. CONAWAY.
